UNITED STATES PATENT OFFICE.

WILLIAM WARFIELD CARDER, OF OLDTOWN, MARYLAND.

GARMENT-SUPPORTER.

SPECIFICATION forming part of Letters Patent No. 632,641, dated September 5, 1899.

Application filed June 19, 1899. Serial No. 721,059. (No model.)

To all whom it may concern:

Be it known that I, WILLIAM WARFIELD CARDER, of Oldtown, in the county of Allegany and State of Maryland, have invented 5 a new and Improved Garment-Supporter, of which the following is a full, clear, and exact description.

The object of my invention is to provide a garment-hanger especially adapted for hanging trousers, and to so construct the device that it may be applied with equally good results to thick and to thin garments and which will remain in a full open position until intentionally closed.

15 A further object of the invention is to construct the device so that it will be light, strong, compact, and economic, and so that the weight of the garment when the supporter is hung up will tend to promote the clamping action 20 of the jaws of the device.

The invention consists in the novel construction and combination of the several parts, as will be hereinafter fully set forth, and pointed out in the claims.

25 Reference is to be had to the accompanying drawings, forming a part of this specification, in which similar characters of reference indicate corresponding parts in both figures.

Figure 1 is a perspective view of the im- 30 proved device; and Fig. 2 is a transverse vertical section through the device, illustrating in dotted lines the position of the parts when the jaws are opened to receive a garment.

Two jaws A and B are employed, and these 35 jaws are usually of the same length and may be made of any desired material. Preferably the said jaws are rectangular in cross-section. In connection with the jaw A a horizontal bearing C is employed, which bearing is sub- 40 stantially U-shaped and is supported by standards 10, that enter the jaw A, one at each side of the center of said jaw. The free ends of the bearing extend beyond the inner face of the jaw A, while the bow portion or member 45 of the bearing C is over the upper edge of the said jaw A, as shown best in Fig. 2. The bearing C and its standards are usually made from one piece of wire of suitable gage, and after the bearing C has been formed the wire 50 is returned from the free ends of the side members of the bearing to the bow member, forming additional side strands 11, of which

the standards 10 are continuations. In forming the bearing C and its standards 10 eyes 12 are produced at the free ends of the side mem- 55 bers, as shown in both figures.

The jaw B is pivoted in a bail D, which bail consists of a central yoke-section 13, the upper portion whereof at its sides is held to turn in the eyes 12 of the bearing C, and the bow 60 member of the yoke 13 consists of a crank-arm 14, that occupies a horizontal position between the side members of the bearing C when the jaws A and B are closed. The bail is completed by extending arms 15 in opposite 65 directions from the bottom of the side members of the yoke 13, and these arms extend along the upper edge of the jaw B in direction of its ends. Each arm 15 is provided with a downwardly-extending crank-terminal 70 16, which crank-terminals are pivoted centrally in the ends of the jaw B, as shown in Fig. 1.

A hook 17 is used to hang the device from any suitable support. This hook is prefer- 75 ably provided with a twin shank 18, the mem- bers of the shank being attached to the central portion of the upper crank 14 of the bail D, and the members of the shank are slightly separated where they connect with the yoke 80 13, so as to form a guide for a spring-arm 19, which arm extends from the bow-section of the bearing C to an engagement with the under surface of the crank 14 of the bail D and beyond the said crank in direction of the jaw 85 B. The spring-arm 19 terminates at its free end in an enlargement 20, and the inner end of the spring-arm is formed in a coil which encircles the bow portion of the bearing C. The opposite end of the spring-arm is attached 90 to a side member of said bearing, as shown in Fig. 2. This spring-arm 19 serves to hold the crank 14 in horizontal position and the jaws A and B in contact with each other or with a garment that is placed between them. 95

It is evident, since the hook 17 is attached to the crank 14 of the bail D, that when the device is supported by said hook the hook sustaining the weight of the device and attached garment will act to cause the jaws to 100 press closely together and prevent them from becoming accidentally separated. When the jaws are opened to their full extent, as shown in dotted lines in Fig. 2, the jaw B is carried

away from the jaw A and the crank 14 of the bail is given a downward inclination, pressing the spring-arm 19 also downward, and when the crank 14 reaches the enlargement 5 20 of the spring-arm the arm and crank will so bind as to hold the jaw B in its projecting position. As the jaw B is moved to its open position it first moves parallel with the jaw A and then slightly upward. This movement is consequent upon the pivotal connection of the jaw B with its bail D.

Having thus described my invention, I claim as new and desire to secure by Letters Patent—

15 1. A garment-supporter consisting of opposing jaws, a horizontal bearing located above and attached to one of the jaws, a bail pivotally attached to the opposing jaw, said bail being adapted to turn in said bearing 20 and being provided with a crank between its points of engagement with the bearing, and a spring carried by the bearing and having engagement with the under surface of the crank or bail, for the purpose described.

25 2. A garment-hanger consisting of opposing jaws, a horizontal bearing located above

and attached to one of the jaws, a bail pivotally attached to the opposing jaw, which bail is held to turn in the said bearing and is provided with a crank-arm between its points of engagement with the bearing, a suspension device connected with the crank-arm of said bail, and a spring-arm having bearing against the under surface of the crank-arm of the bail, which spring-arm is provided with a section coiled around and attached to the bearing, for the purpose set forth. 30 35

3. A garment-hanger, consisting of opposing jaws, one having a member rising therefrom and offset laterally to extend over the 40 opposing jaw and having a horizontal bearing, a bail attached to the opposing jaw which bail is held to turn in the said bearing and is provided with a crank-arm between its point of engagement with the bearing, the crank-arm extending inwardly toward the first-named jaw, and a suspension device connected with the crank-arm of said bail. 45
